[57] **CLAIM**

The ornamental design for a compact disk holder, as shown and described.

DESCRIPTION

FIG. 1 is a top perspective view of a compact disk holder showing a first embodiment of my new design;
FIG. 2 is an elevation view from one side thereof;
FIG. 3 is a top plan view thereof;
FIG. 4 is a bottom plan view thereof;
FIG. 5 is another elevation view thereof taken from the side opposite that shown in FIG. 2; and,
FIG. 6 is a top perspective view of a compact disk holder showing a second embodiment of my new design.
